UNITED STATES PATENT OFFICE.

FREDERICK B. PALMER, OF CHICAGO, ILLINOIS.

DESIGN FOR A BURNER FOR LAMPS.

SPECIFICATION forming part of Design No. 30,620, dated April 25, 1899.

Application filed March 27, 1899. Serial No. 710,720. Term of patent 3½ years.

To all whom it may concern:

Be it known that I, FREDERICK B. PALMER, a citizen of the United States, residing at Chicago, in the county of Cook and State of Illinois, have invented and produced a new and original Design for a Burner for Lamps, of which the following is a specification, reference being had to the accompanying drawings, forming part thereof.

10 Figure 1 is a view in elevation of a burner for lamps, showing my new design. Fig. 2 is a similar view of the burner, looking in another direction. Fig. 3 is a bottom plan view. Fig. 4 is a top plan view. Fig. 5 is a plan sectional view taken on line 5 5 of Fig. 1, and Fig. 6 is a vertical sectional view taken on line 6 6 of Fig. 2.

As shown in the drawings, the leading or material features of my design consist of a 20 hollow cylinder portion A, having an external annular flange a on its lower portion, and a reduced cylindrical or tubular portion B below said flange. Extending downwardly from the flange a are two tubular pieces b and b', 25 which are joined together by a portion b² at

their lower ends. Extending at a right angle from the lower portion of the tube b' is a tubular piece c, having internal screw-threads, and extending at a right angle from the lower portion of the tube b is a tubular piece c', having external screw-threads.

The above-named parts are made of one piece, or, in other words, are integral. The portions b, b', and b² each have openings d extending from their lower ends to and communicating with channels d', provided horizontally in the flange a on the lower portion of the tubular piece A, whose cavity is contracted, as at a². (See Figs. 4 and 6 of the drawings.)

Having described my invention, what I claim as new, and desire to secure by Letters Patent, is—

The design for a burner for lamps, substantially as herein shown and described.

FREDERICK B. PALMER.
